RADIATOR

Harry Jaffe, Chicago, Ill., assignor to Sears, Roebuck and Co., Chicago, Ill., a corporation of New York

Application October 19, 1932, Serial No. 638,443

4 Claims. (Cl. 257—136)

This invention relates to heat-exchange and air-conditioning apparatus, as, for example, radiators for heating rooms in dwellings and other buildings, and apparatus for cooling rooms. The invention relates particularly to the fins employed to facilitate the conduction of heat from or to a source of heating or cooling fluid. As heretofore commonly constructed, such fins have been made of a single thickness of thin sheet copper, the fin being either flat or corrugated, but in either case being readily deformable by accident or careless use so as not to be regularly spaced along the steam or other pipe on which they are mounted. When thus bent out of proper relation to one another the efficiency of the radiating unit is reduced. Such fins also have produced a relatively great increase in the weight of the radiating unit.

Various other forms of fins have been proposed, but they have been objectionable on account of inefficiency, weight, and expense.

One of the objects of my invention is to produce a heat-conducting fin which shall be highly efficient, light in weight, sufficiently rigid so as not to be readily deformable, and relatively inexpensive.

Another object of the invention is to provide an improved form of radiator of the baseboard or floorline type.

In the accompanying drawing, Figure 1 is a perspective view of a radiator embodying my invention. Fig. 2 is a transverse vertical sectional view of the radiator. Fig. 3 is a fragmental longitudinal sectional view. Figs. 4, 5 and 6 are perspective views of several forms of fins constructed in accordance with the invention.

The size and shape of a radiating fin embodying features of my invention will vary with the number of heat-exchange tubes upon which it is to be mounted. The number of tubes may vary from one to as many as may be required for the purpose in hand. The present drawing shows several different forms of fins. Fig. 4 shows a fin A of oblong form adapted to be mounted upon two tubes. The fin comprises a hollow body composed of thin sheet copper or other metal which is a good conductor of heat. For the sake of clearness, the thickness of the metal has been much exaggerated in the drawing. The fin is composed of two substantially similar halves 1, these halves being of oblong form and being united at their perimeters in any preferred manner, as by folding the edges of one half to clamp the edges of the other, as shown at 2 in Fig. 4. The fin is provided with annular

flanges 3 to receive the heat-exchange tubes 4. These flanges are formed integral with the halves composing the body. The flanges upon one fin contact the flanges of adjacent fins and thus serve to space the fins apart uniformly upon the tubes 4. If desired, the sides of the body may be stiffened by pressing the sheet metal into the form of ribs 5 radiating from the flanges 3.

In the form of fin shown in Fig. 4, the hollow body is not sealed, but on the contrary, is formed to permit air to flow through the fin. As illustrated in Fig. 4, openings 6 are formed in each half of the body at its upper and lower edges so as to permit air to enter at one edge of the body and flow out at the other.

The fin B illustrated in Fig. 5 is similar to the fin A except that the body is sealed or substantially closed, instead of being provided with openings such as 6.

In Fig. 6 I have shown a form of fin C which is intended to be mounted upon a single tube and which may therefore be circular in form, as shown, if desired.

Fins embodying the features of my invention may be used in connection with heat-radiators, refrigerators or coolers, and apparatus intended for either heating or cooling. Such radiators or cooling apparatus may partake of various forms and may be mounted in various ways in relation to the space to be warmed or cooled. It is common practice to place radiators on the floor, on the wall, or within the wall. Fins embodying my invention may be employed in connection with radiators mounted in any of these ways.

In Figs. 1, 2 and 3 I have shown a radiator of the type which is arranged to extend along the baseboard within a room. In the present embodiment of the invention, the body of the radiator comprises a back wall 10, a short upwardly and forwardly inclined top wall 11, a forwardly and downwardly curved bottom wall 12 and end walls 13. Within said body is a radiating unit composed of two headers 14, two tubes 4 and a series of fins mounted upon said tubes and filling the space between the headers.

The fins may be secured to the heat exchange tubes 4 in any preferred manner, but preferably by submerging the lower portions of the fins after they have been assembled on the tubes, in a bath of acid and then in a bath of molten solder or the like until the annular flanges 3 are approximately one-half submerged, capillary action serving to cause the solder to flow up around the flanges so as to unite them to the tubes. This

radiating unit is mounted within the radiator body by means of a screw stud 15 secured to the rear end of each header 14 and extending through an opening in the back wall 12, and a nut 16 turned on the screw stud. The steam pipes 17 and 18 extend through openings in the end walls 13 and are screwed into the headers 14.

Air inlet openings are provided in the lower portion of the radiator body, as by means of a 10 grid 19 attached to the forward edges of the bottom wall 12 and the end walls 13. This grid extends vertically and forms the lower portion of the front wall of the radiator body.

The radiator body is provided with outlet openings by means of a grid 20 secured to the forward edges of the top wall 11 and the end walls 13. This grid extends forwardly and downwardly and constitutes the upper portion of the front of the radiator body.

20 The grids 19 and 20 extend to points adjacent the radiating unit, the opening or space between the lower edge of the grid 20 and the upper edge of the grid 19 being closed by means of a removable cover 21. This opening extends longitudinally of and in front of the radiating unit. While the cover 21 may be mounted and held in place in various ways, I have herein shown the lower edge of the grid 20 as being bent to form a flange 22 which is the equivalent of a hook, the 25 upper edge of the cover being similarly bent to form a hook 23. The upper edge of the grid 19 is bent to provide a resilient locking flange 24. The lower edge of the cover 21 has a coacting locking flange 25 which may be sprung over the 30 flange 24 to hold the cover in place.

As indicated by the dotted lines 26 in Fig. 2, the rear edges of the radiating fins are spaced from the back wall 10 and the front edges of the fins are spaced from the cover plate 21.

40 The radiator is supported above the floor by means of a plurality of feet 27 of any preferred form secured to the bottom wall 12.

In operation, heat is radiated from the tubes 4 through the fins, thus producing a flow of air 45 upwardly through the radiator body, the air entering the grid 19 and passing up through the spaces between the radiating fins and out through the grid 20.

Access may be had to the radiating fins when 50 it is desirable to brush off an accumulation of dust or the like, by pulling the lower edge of the cover plate forwardly to disengage it from the locking flange 24, whereupon the plate may be lifted out of engagement with the bent flange 22.

55 It will be seen that the heat-conducting fins herein disclosed are rigid and light. Tests have shown them to be greatly superior in efficiency to fins of the prior art. Moreover, since the fins are soldered to the tube, there is no gradual loss 60 of efficiency due to corrosion or dust entering spaces between the tube and the fin, as in prior constructions.

The radiator shown in Figs. 1, 2 and 3 is much

lighter and more efficient than prior radiators of the same type. The efficiency of the fins is so great that they may be made relatively small, thus allowing them to be spaced from all sides of the radiator body and thereby permitting a 80 freer flow of air than has been possible with prior constructions. The removable cover plate 21 provides easy access to the radiating fins when dusting becomes desirable.

I claim as my invention:

1. In a heat-exchange apparatus, a tube for the heating or cooling medium, and a series of hollow fins mounted on said tube, each fin having on each side an annular flange surrounding the tube and spacing the adjacent fins uniformly along the tube. 85

2. A radiator comprising, in combination, a body comprising a sheet of metal bent to form rear, top and bottom walls, sheet-metal end walls permanently secured thereto, and a pair of grille members extending downwardly from the top wall and upwardly from the bottom wall respectively and permanently secured to the front edges thereof and to the end walls, the adjacent edges of said grille members being spaced from each other, a 90 radiating unit comprising a tube and a series of radiating fins mounted on said tube, said unit being positioned within said body opposite the space between the adjacent edges of said grille members and being supported by said rear wall, and 95 a cover plate for closing said space comprising a sheet-metal member hooked to the edge of one of said grille members and having a detachable connection with the edge of the other grille member. 100

3. A radiating fin adapted to be mounted on a tube comprising a pair of sheet-metal dished members with their concave sides facing each other, said members having perimetral flanges extending outwardly from the dished portion and united in abutting relation to form a relatively 110 stiff heavy portion at the perimeter of the fin, the dished portion of each member having an opening and an annular flange to fit snugly over the tube, said annular flange extending from the convex side of the member, and stiffening ribs formed 115 in the dished portion of each member extending radially from said opening. 120

4. A radiating fin adapted to be mounted on a heat-exchange tube comprising, in combination, a pair of dished members with their concave 125 sides facing each other, each member being made of sheet metal and comprising a relatively flat central portion, an angularly extending portion bordering said central portion, and a perimetral flange abutting and rigidly secured to the flange 130 on the other member, the angularly extending portions of both members being cut away along parts of the upper and lower edges to form openings to permit air to flow through the body but leaving the perimetral flanges intact to maintain 135 the stiffness of the members. 140

HARRY JAFFE.
